UNITED STATES PATENT OFFICE.

FRANKLIN M. REED, OF INDIANAPOLIS, AND CORNELIUS R. UMBENHOWER,
OF PENDLETON, INDIANA.

HEATING-STOVE.

SPECIFICATION forming part of Letters Patent No. 660,123, dated October 23, 1900.

Application filed November 17, 1899. Serial No. 737,348. (No model.)

To all whom it may concern:

Be it known that we, FRANKLIN M. REED, of Indianapolis, county of Marion, and CORNELIUS R. UMBENHOWER, of Pendleton, county of Madison, State of Indiana, have invented a certain new and useful Heating-Stove; and we do hereby declare that the following is a full, clear, and exact description thereof, reference being had to the accompanying drawings, in which like figures refer to like parts.

Our invention relates to a heating-stove for burning gas or other fuel.

What we claim as our invention will be understood from the following description and claims and the accompanying drawings, illustrating one form of stove embodying our invention.

In the drawings, Figure 1 is a central vertical section of said stove. Fig. 2 is a plan of the oil-pan or bottom of the burner. Fig. 3 is a plan of the diaphragm on which the burner is mounted. Fig. 4 is a section on the line A A of Fig. 1.

In detail we show herein a stove containing a base 1, supported upon legs 2 and with a shell 3 extending upward from the base in which the burner is located and which constitutes the fuel-chamber. The shell is continued to form the upper part 4. These parts, however, in the stove shown form one shell with a contracted portion between the parts 3 and 4. On the upper end of part 4 of the shell the top 5 is mounted on a ring of open-work 6.

7 is the bottom of the base.

8 is the door, and 9 is the outlet to the flue.

Within the upper portion of the shell of the stove we suspend an internal heating-chamber 10, pointed at its lower end and central over the burner or the fire-chamber and of less diameter than the upper shell, so that the fuel-chamber surrounds said internal heating-chamber 10. This internal heating-chamber is open at the upper end to the outside air through the open-work 6. The outlet to the flue is at the upper end of the outer or fuel chamber. With this arrangement, therefore, the flames and heat from the fuel envelop said internal heating-chamber and pass

up around it and out through the flue. Therefore in addition to the outer heat-radiating surface we have the heat-radiating surface of said internal chamber 10, thus substantially doubling the heat-radiating surface. Another effect of this construction is that since the internal heating-chamber 10 is centrally located it drives the heat and flame against the outer shell of the stove, thus bringing the heat or flames in direct contact with said outer shell instead of allowing the heat and flame to pass directly up through the middle of the stove and out through the flue without imparting the heat to the wall of the stove, as is true of stoves in the usual form. In this stove the heat and flame in their passage up through the stove are in direct contact simultaneously with both the inner and outer shells. To render said construction further effective, means is provided for introducing air to the lower end of the internal chamber through the conduit 13, which in the form shown leads from the bottom of the shell or stove up past the fire-chamber, whereby the air is somewhat heated before it enters the internal chamber. We also provide a conduit 15, leading likewise from the bottom of the stove up past the fire into the upper part of the fire-chamber, whereby the air is somewhat heated and in that condition is introduced through the openings 16 directly upon the flame or fuel. The wall 14 separates conduits 13 and 15. This introduction of superheated air at the point indicated into the fire-chamber causes it to mix with the smoke and gases, which results in their complete combustion.

Between the base and the fire-chamber 3 we cast an annular ring 21, upon which we place the diaphragm 20, so that it is readily removable. Said diaphragm is centrally open and has inwardly-extending arms 22, that are provided with upwardly-extending lugs 23. Upon the arms 22 we place the bottom piece 24 of the burner, so that it is held in place by the lugs 23. Said bottom is centrally apertured, and has around said aperture a sleeve 25, through which the oil-pipe 26 extends upward. Said bottom 20 has an exter-

nal rim 27 and a series of openings 28, which are also protected by upwardly-extending walls 29, whereby the oil cannot escape through said bottom, but air can readily pass up through it for combustion purposes.

On the upper end of the oil-pipe 26 we mount an outlet-dome 30, the opening therefrom being central, whereby the oil will flow down therefrom in all directions. Surrounding said outlet-dome 30 there is a hood 31, formed like the frustum of a hollow cone, with the base carried on the outer rim 27 of the bottom piece 24. The function of this hood is to confine the heat around the dome 30 and concentrate the heat thereon. The heated air surrounding these parts is confined by the casing 32, that rests upon the diaphragm 20, and has an opening through its top of larger diameter than the hood, which it surrounds, so that the heat by the inturned top of the casing 32 is deflected against the hood 31. The hood 31 is provided with a series of apertures 33 for the escape of heat and intermingling of air and gases. An outlet-pipe 34 leads centrally from the bottom 7 to carry off any overflow of oil.

In this construction of stove either oil, gas, or coal can be burned, as the coal-grate can be substituted for the oil-burner herein shown. Also the oil-burner as here made can be lifted out of the stove without disconnecting or interfering with the oil-supply pipe.

What we claim as our invention, and desire to secure by Letters Patent, is—

35

1. A stove including an outer shell centrally contracted and also contracted near its upper end, a smoke-outlet above the upper contraction, an inner casing located in the upper part of the stove with the body of it 40 between the contracted portions of the outer shell and parallel therewith, the upper end of said casing being open and secured to the stove above the smoke-outlet and the lower end being tapering centrally over the fire-pot, 45 and an air-inlet to the lower end of said inner chamber that leads from the bottom of the stove.

2. A stove including an outer shell with a fuel-chamber in its lower end, an inner casing forming an inner air-heating chamber occupying the central portion of the upper end of the stove, an outlet opening from the upper end of said inner chamber, an air-inlet opening from the bottom of the stove to the 55 lower end of said inner chamber, and an air-inlet into the fuel-chamber just below said inner casing.

In witness whereof we have hereunto affixed our signatures in the presence of the witnesses herein named.

FRANKLIN M. REED.

CORNELIUS R. UMBENHOWER.
